Primary Examiner — T Chase Nelson*Assistant Examiner* — Kelly L Gross(74) *Attorney, Agent, or Firm* — 3M Innovative Properties Company(57) **CLAIM**

The ornamental design for a wound dressing, as shown and described.

DESCRIPTION

FIG. 1 is a top view showing a new design for a wound dressing.

FIG. 2 is a cross-sectional view along lines 2-2; and,
 FIG. 3 is a cross-section view along lines 3-3.

The portions of the wound dressing shown in broken lines are included to show features that form no part of the claimed design.
